United States Patent Office.

SANFORD S. BURR, OF DEDHAM, MASSACHUSETTS.

Letters Patent No. 95,318, dated September 28, 1869.

IMPROVED EXTENSION-CRIB.

The Schedule referred to in these Letters Patent and making part of the same.

To all to whom these presents shall come:

Be it known that I, SANFORD S. BURR, of Dedham, in the county of Norfolk, and Commonwealth of Massachusetts, have made an invention of a new and useful Extension-Crib, for sleeping purposes; and do hereby declare the following to be a full, clear, and exact description thereof, due reference being had to the accompanying drawings, making part of this specification, and in which—

Figure 1 is a perspective representation of my invention in a contracted condition, and

Figure 2, a side representation of it in an extended state,

Figure 3 being a transverse and vertical section of such invention.

The invention comprising the subject-matter of this patent has for its object a child's sleeping-crib; and relates to the construction of such articles, whereby they may be varied in length at pleasure from the size requisite for the smallest child, to that of sufficient capacity to contain an adult, the bed-bottom or foundation being so applied to the crib as to allow its contraction and expansion automatically.

The invention consists in uniting two suitably-formed end portions or frames, whose united length when closed shall constitute the crib in its shortest condition, by means of longitudinal side rails tongued and grooved in such manner that while confining the end portions of the crib together, they permit of their being forced apart to the desired extent, a series of slats, or sacking, or other suitable bed foundation, being applied in manner to accommodate itself to variations in length of the crib, as hereinafter explained.

In the drawings, to which allusion has before been made as accompanying this specification, and which illustrate my invention, *a a'* denote two upright frames or standards, provided with short side rails, *b b' b'*, projecting inwardly in such manner that when in a closed state, their adjacent ends shall abut together and form a continuous side rail of the crib.

To the inner faces of these side rails, or to any proper part of the same, I affix two series of horizontal rails, *c c' c'*, such rails being tongued and grooved, as shown at *d*, in such manner as to maintain the horizontal and vertical parallelism of the end frames and their rails, and at the same time permit of their approaching or receding from each other.

The bed-bottom adopted in the present instance consists of a series of parallel horizontal slats, *e e e*,

resting upon the top of the sliding rails, and confined together in proper manner by cords *f f*, or their equivalents, these cords being of such a length as to correspond to the extreme length of the crib or bed when extended to its fullest length.

In practise, however, various substitutes for the slats may be adopted without affecting the characteristic feature of my invention.

The operation of the crib will readily manifest itself to intelligent persons, as by forcing apart its end portions its length may be prolonged to any extent from that necessary for an infant to that suitable for a bed for adults, the transformation being accomplished easily and expeditiously.

Among the advantages to be found resulting from the use of my invention, as above described, may be enumerated the following:

First, when in use as a sleeping-place for infants or young children, it is reduced to such contracted bulk as to occupy much less space in an apartment than any analogous article heretofore made.

Second, while in a closed state, occupying very little space, the above-described crib may be varied in length according to the growth of the child, or extended to such a length as to form a comfortable bed for adults, thus producing an article of furniture which shall alike serve the purposes of a perfect crib for children of any age, or of a bed for grown people, at a small cost.

Having thus described the nature of my invention, as well as its objects and advantages,

What I claim to be novel and original with myself, and desire to secure by Letters Patent of the United States, is as follows:

Claims.

1. I claim a child's crib, in which the divided crib-frame proper is combined with the tongued and grooved side rails *c c'*, substantially as and for the purposes herein described.

2. I claim in a crib or bedstead, made as herein explained, combining therewith the bed-bottom, substantially in the manner described, so that the bed-bottom shall automatically accommodate itself to the variations in length of such crib or bed, for the purposes essentially herein set forth.

SANFORD S. BURR.
